UNITED STATES PATENT OFFICE.

ROBERT GAWNE, OF TOLEDO, OHIO.

PROPELLER FOR VESSELS.

SPECIFICATION forming part of Letters Patent No. 244,582, dated July 19, 1881.

Application filed April 26, 1881. (Model.)

To all whom it may concern:

Be it known that I, ROBERT GAWNE, of Toledo, in the county of Lucas and State of Ohio, have invented a new and useful Improvement in Propellers for Vessels, of which the following is a full, clear, and exact description.

The invention consists in combining a pinion having a notched hub, a loose sleeve having a notched flange, a cylinder having a stud, and an engine drive-shaft having a pinion, with a cylinder carrying an eccentrically-arranged propeller-shaft, as hereinafter described.

In the accompanying drawings, Figure 1 is a sectional side view of the stern portion of a boat fitted with the improved mechanism. Fig. 2 is an end view at the stern, and Fig. 3 is a plan view.

Similar letters of reference indicate corresponding parts.

A is a hollow cylinder, fitted in the vessel E at the stern and extending through the stern-post below the water-line. The cylinder extends within the vessel to near the engine, and its diameter will be proportioned to the extent of rise and fall it is desired to obtain for the propeller. It is sustained at the stern-post by a box, a, suitably packed to prevent inlet of water, and the inboard end is sustained in a box on a pillow-block, b.

Through the cylinder A passes the shaft c, carrying propeller d, and at the inner end fitted with a pinion, e, for connection of power. The shaft c is eccentric to the axis of the cylinder, being placed as closely as may be to the side thereof, and is sustained by boxes f, f, attached upon end plates, g, g, that close the ends of the cylinder. There is a packing-gland, h, on the shaft at the inner box, to prevent leakage.

Around the cylinder A is a brake-strap, i, connected with a hand-lever, k, that is placed for engagement with a notched bar so that by operating the lever the strap will clamp the cylinder and hold it from turning.

On the end of shaft c next to the pinion e is a loose sleeve, l, notched to engage with the notched hub of the pinion, and prevented

from turning on the shaft by a stud that projects from the cylinder and engages a notched flange of the sleeve. The sleeve l may be otherwise connected to the cylinder, so that when it is engaged with the pinion the shaft c shall be prevented from turning and the driving-power exerted on the cylinder. A lever, m, connected with sleeve l, serves for moving the sleeve in and out of engagement with the pinion.

The driving-shaft (shown at n) is placed in line with the central axis of cylinder A and carries a large gear-wheel, o, that meshes with pinion e. The pinion will thus be always engaged in any position to which the cylinder may be turned.

It will be seen that by a semi-rotation of cylinder A the propeller is shifted from the highest to the lowest point, and can be thus positioned according to the load or the depth of the water. With a light load the propeller can be brought down into the water to obtain effective action, and with a deep-loaded boat the propeller can be raised in shallow water, as may be necessary.

To move the cylinder and raise or lower the propeller the clutch l is to be moved by its lever and engaged with pinion e. The propeller-shaft being thus stopped, the pinion will travel upon the wheel o and the cylinder will turn. The clutch is to be released as soon as the propeller is in the desired position, and the brake then applied to the cylinder.

This mechanism can also be utilized to prevent the boat making leeway by wind at either side. For this purpose the propeller will be shifted to either side of the center, as required, and will then act to work the boat out and prevent it from being blown on the banks.

The propeller is fitted with an annular band, p, secured upon the ends of the blades. This protects the blades from injury and serves to prevent the water from being thrown out sideways.

This propelling mechanism can be readily and inexpensively applied to ordinary boats.

I am aware that a drum or cylinder having the propeller-shaft eccentrically arranged

therein and provided with a flange toothed to mesh with a worm on a crank-shaft adapted to be adjusted and operated by hand is not new; but

5 What I claim is—

In a vessel having a propeller driven by an engine and the hollow cylinder A at the stern, the propeller-shaft *c*, arranged eccentrically to the axis of the cylinder and connected with

the engine drive-shaft by ratchet-clutch mechanism, substantially as described, whereby the cylinder may be turned with engine-power, to raise or lower the propeller, as set forth.

ROBERT GAWNE.
